UNITED STATES PATENT OFFICE.

HARRY AIDENLAND, OF TOLEDO, OHIO.

COMBINED HOOD AND SCARF.

1,211,807.

Specification of Letters Patent.

Patented Jan. 9, 1917.

Application filed June 8, 1916. Serial No. 102,407.

To all whom it may concern:

Be it known that I, HARRY AIDENLAND, a citizen of the United States, residing at Toledo, in the county of Lucas and State of Ohio, have invented new and useful Improvements in Combined Hoods and Scarfs, of which the following is a specification.

My invention relates to a combined hood and scarf, and has for its object to provide an article of apparel of the kind that is of simple and economical construction, and adapted to serve both as a becoming covering for the head and a scarf for the neck, and that is susceptible of being arranged in various forms and styles, according to the individual tastes of the wearers. I accomplish these objects by the construction and combination of parts, as hereinafter described and illustrated in the drawings, 20 in which—

Figure 1 is a blank formed of a single piece of fabric that is adapted to be formed into a combined hood and scarf, constructed in accordance with my invention. Fig. 2 is a side view of the hood formed from the blank shown in Fig. 1, by folding the blank on the dotted central line of Fig. 1 and stitching together certain of the coinciding margins and leaving the others open. Fig. 3 is a three quarter back view of the hood draped in one form on the head, neck and shoulders of a wearer. Fig. 4 is a side view of the same. Fig. 5 is a similar view of the hood draped in a different fashion. Fig. 6 shows the hood draped in still another way, and Fig. 7 shows the hood applied as a cape for the shoulders.

In the drawings in which the same reference numerals indicate the same parts, 1 designates a blank cut from a piece of fabric to the form shown in Fig. 1, and having the equal edges $a-a$, $b-b$, $c-c$, $d-d$, $e-e$ and $f-f$. The blank 1 doubled on itself on the dotted line g , with each pair of edges 45 coinciding, is formed into a hood having scarf portions 2, 2 by stitching together respectively the pairs of edges $a-a$, $b-b$ and $c-c$ forming the hood 3, and leaving the edges $d-d$, $e-e$ and $f-f$ open. Thus 50 constructed, the surplus pointed portions 4

and 5 (as defined by dotted line h in Fig. 2) respectively lie above the top and back portion of the crown, when the hood is placed on the head with the face projecting from between the curves of the edges 55 $e-e$. Before placing the hood on the head the pointed surplus portions 4 and 5 may be folded and secured on opposite sides of the crown portion, as shown in Figs. 3 and 4, or together and extending rearward, as 60 shown in Fig. 5, or one forward and the other rearward, as shown in Fig. 6, and when placed on the head the hood will present the respective effects shown in the Figs. 3, 4, 5 and 6, or if dropped down from the 65 head over the back and shoulders, as shown in Fig. 7, it will assume the form of a pointed cape.

The pointed surplus portions 4 and 5 are adapted for ornamentation by embroidery 70 or the like, whereby the hood is made to further express the individual taste of the wearer.

It is manifest that by changing the angle and increasing the length of the edges a , b 75 and c of the blank upward, the lengths of the triangular folds adapted to be formed of the surplus portions will be increased, without departing from the principle of construction of the hood that adapts it to 80 the draping effects shown and described, and I therefore do not limit myself to the exact angles of the top and side edges of the body portion of the blank forming the hood, other than as expressed in the claim. 85

What I claim to be new is—

A combined hood and scarf formed of a blank of fabric having two equal side edges and a W shaped top edge, adapted to form a hood portion, and two equal elongated extensions from the body of the hood portion opposite the inner angles of the top edge and having equal outer edges incurved from and extending the side edges of the hood portion and two equal inner edges oppositely outcurved from a line bisecting the middle outer angle of the top edge at a distance less than the lengths of the side edges of the hood portion, the hood adapted to be formed by folding the blank on said 100

bisecting line and stitching together the coinciding side and top edges of the hood portion, said hood having foldable pointed surplus portions at the closed end of the hood and scarf extensions from its lower and open end.

In testimony whereof I have hereunto set

my hand at Toledo, Ohio, this 27th day of May, 1916.

HARRY AIDENLAND.

In presence of—

**ALBERT T. GOORLEY,
RICHARD D. WATSON.**
